MINNESOTA CEMENT PRODUCTS COMPANY, OF MINNEAPOLIS, MINNESOTA, A COR-
PORATION OF MINNESOTA.

CONCRETE LAMP-STANDARD.

1,339,220.

Specification of Letters Patent. Patented May 4, 1920.

Application filed February 3, 1919. Serial No. 274,711.

To all whom it may concern:

Be it known that we, ELMER G. PERL and LEIGH C. Boss, citizens of the United States, residing at Minneapolis, in the county of 5 Hennepin and State of Minnesota, have invented certain new and useful Improvements in Concrete Lamp-Standards; and we do hereby declare the following to be a full, clear, and exact description of the invention, such as will enable others skilled in the art to which it appertains to make and use the same.

Our invention has for its object to improve the construction and to facilitate the 10 erection of reinforced concrete lamp standards, and to such ends, generally stated, the invention consists of the novel construction and combination of parts hereinafter described and defined in the claims.

20 Hitherto, in the erection of lamp standards for electric lamps, it has been customary and deemed necessary to provide small man-holes near to, but outside, of the base of the standard or lamp supporting column, 25 for containing various electrical devices, such as disconnections between the light and column wires, switches and fuses, some of which, and frequently all of which are enclosed. This kind of installation is expensive. 30 Moreover, it has not hitherto been an easy matter to anchor concrete lamp standards, and in some places it has been impossible or impracticable to apply them.

This invention provides the standard or 35 column, in its base, with a cast or metal shell which will serve three functions, to wit, first, that of a reinforcement to the base of the standard or column; second, as an anchoring device for anchoring the column to its 40 foundation; and third, as a housing for the electrical connections, switches and fuses. Because of the latter noted functions of this cast shell, a manhole or box outside of the standard or column is not necessary.

45 The invention is illustrated in the accompanying drawings, wherein like characters indicate like parts throughout the several views. Referring to the drawings;

Figure 1 is an elevation showing one de- 50 sign of the lamp standard;

Fig. 2 is an elevation of the lower portion of the standard, some parts being sectioned;

Fig. 3 is a vertical section taken on the line 3—3 of Fig. 4; and

Fig. 4 is a horizontal section taken on the line 4—4 of Fig. 2.

The concrete body of the column is indicated by the numeral 5. The metallic shell, which is preferably a casting, is indicated as an entirety, by the numeral 6 and it is 60 made downwardly flaring or approximately bell-shape, but of a size considerably smaller than the base of the standard, so that it will be completely covered by the concrete of the base. The body of the standard is preferably cast with an axial hole, and surrounding this hole it is reinforced by vertical rods 7 around which the concrete of the column is cast. The sheet 6, on its base flange, is formed with a plurality, as 70 shown, of four vertically perforated bosses 8 through which anchoring bolts 9 are adapted to be passed. The lower ends of these anchoring bolts 9 will be cast into the concrete foundation 10 and at their threaded upper ends, they are provided with nuts 11 that engage the tops of the bosses 8. The concrete base of the column is provided with depressions 12 in line with the bosses 8, so that the nuts 11 will be countersunk within 80 the same. These depressions 12 may be filled with concrete or cement after the column has been properly set and properly anchored down by tightening of the nuts 11. On its exterior, the metal shell 6 is 85 provided with one or more outstanding anchoring flanges 13 which assist in anchoring the said shell to the base of the column. At one side, the shell 6 is formed with a downwardly and outwardly flaring endless 90 flange 14 that affords an entrance for the hand or hands from the exterior of the column. The rim of this flange 14 is so formed that it carries out the design of the exterior of the column and the opening therein is 95 adapted to be closed by a lid 15 shown as detachably secured in place by nut-equipped bolts 16. This lid or closure plate may, of course, be made ornamental or plain, as desired. Within, the cast shell 6, is shown as 100

provided with an inwardly projecting flange 17 to which the various devices, such as a switch, fuse plug, or the like, may be attached.

5 From the foregoing it is evident that the cast-in metal shell not only reinforces the base of the column but is rigidly tied to the upper portion of the column and that it is this shell that is directly anchored to 10 the foundation. The anchoring strain is therefore, transmitted from the foundation, first to the said metal shell and from thence is distributed through the column. In practice, the anchoring bolts 9 can be properly 15 set in advance at any suitable place in any concrete foundation, or elsewhere, and the erection of the column requires only that the column be properly set on these bolts and the nuts of the bolts tightened. When 20 the column is set, it is a complete device having a receptacle for switches, electrical connections, fuses, and the like, making unnecessary any other provision for the installation of such device. The connections from 25 the lead wires which will be in the foundation, are simply brought up into the column and properly connected and these connections may be made after the column is set on its foundation. Moreover, the connections 30 may be changed at any time, while the column is set on its foundation. For example, switches can be installed or removed and operated at will. This, therefore, provides a very simple way in which columns 35 may be equipped with switches, so that when desired, any desired number of lamps primarily connected in series, may be thrown into or out of action. For city street light installations, this is highly de- 40 sirable, because it will frequently happen,

for example, that alternate lights will be sufficient or all that will be desired for lighting purposes.

What we claim is:

1. A monolithic concrete column and base 45 having cast therein a hollow metallic anchoring shell that is provided at one side with a manhole forming flange that extends to the exterior of the column.

2. A monolithic concrete column and base 50 having cast therein a hollow metallic anchoring shell that is provided at one side with a manhole forming flange that extends to the exterior of the column, and metallic anchoring rods extending from the top of 55 said anchoring shell upward into the bottom of the column.

3. A monolithic concrete column and base having cast therein a hollow metallic anchoring shell that is provided at one side 60 with a manhole forming flange that extends to the exterior of the column, and a detachable cover plate for the manhole designed to follow the outline of the exterior of the column.

4. A monolithic concrete column and base having cast therein a hollow metallic anchoring shell that is provided at one side with a manhole forming flange that extends to the exterior of the column, the said 70 anchoring shell being of bell shape form and having an outstanding anchoring flange below said manhole flange.

In testimony whereof we affix our signatures in presence of two witnesses.
